UNITED STATES PATENT OFFICE

2,329,259

FENCE PANEL

Herbert H. Freeman, Minneapolis, Minn.

Application October 8, 1941, Serial No. 414,109

1 Claim. (Cl. 256—23)

The object of my invention is to provide a pendulous fence-panel, which, by oscillation thereof, will permit lawn-mower operation from post to post along the fence line.

In the drawing I have shown my device as adapted to an iron fence, but I do not wish to be limited to metal fence construction, as pivotal and locking members may be attached to panels of fences of wooden construction.

In the drawing like numerals refer to like parts throughout the views.

Fig. 1 is a side elevation of a post and contiguous section of a fence panel.

Fig. 2 an end elevation of same with the post interposed between the observer and the pendulous panel, showing the panel swung laterally to permit operation of a lawn-mower, post to post, along the fence line. The pendulous panel may be thus held by any convenient prop and the prop moved panel-to-panel as required.

Fig. 3 is a plan of the bolt-action lock-piece member and its reach-rod attachment to the turn-button located at approximate mid-panel on bottom panel rail, 3'.

In the drawing: 1 is the supporting post, projecting from which is the superiorly disposed fixed pivotal lug 2, from which the panel is suspended by means of the top panel rail 3 or a longitudinal extension therefrom, resting thereon completing the pivotal ensemble. The lug 2' on opposite side of post is for the obvious purpose of supporting a contiguous panel. A longitudinally movable collar 12 encircling said pivotal members, is secured to top panel rail 3 by set-screw 13, thus ensuring their contiguity, even though the panel be completely revolved vertically. Only two pickets 4, 4' are shown, one of which, 4, passes through a slot 10 in the bolt-action lock-piece member 5, which slides longi-

tudinally on the bottom panel rail 3', the longitudinal movement of said lock member being limited by said picket. (See Fig. 3.)

5 The lock member 5, one at each end of panel and made "right" and "left" to bring extension 7 and turn-button 14 on same side of rail 3', has a lip 6, which, when inserted in the slot or recess 9 (9') in the post 1, prevents panel oscillation; said lock-members being operated by means 10 of reach-rod 8 (8') loosely riveted to the extension 7 of the lock-member and to a turn-button 14, located on rail 3' at a point where it can be conveniently reached by one standing midway of the panel.

15 What I claim and desire to secure by Letters Patent is:

In combination with a pair of supporting posts, a lug projecting from each post and rigidly fixed thereto, a pendulous fence panel including a top horizontal rail between said posts, means pivotally suspending said panel from said lugs comprising a collar slidably mounted on each end of said rail and each collar receiving therein an adjacent lug, a set-screw on each collar for securing the same in adjusted position on its associated rail end, a bottom horizontal rail on said panel, a sliding bolt-action locking member on each end of the bottom rail having a rectangular slot through which a picket, or other top and bottom rail connecting member of said panel, passes for limiting longitudinal movement of said locking member and preventing its removal from said panel, each locking member co-acting with an adjacent post, a turn-button 20 affixed to said bottom rail, and a reach-rod connecting each locking member to said turn-button for effecting simultaneous movement of said locking members.

HERBERT H. FREEMAN.
